UNITED STATES PATENT OFFICE

HEINRICH ZWEIFEL, OF KORNWESTHEIM, AND CARL WILHELM LORENZ MÜLLER, OF FRANKFORT-ON-THE-MAIN, GERMANY, ASSIGNEES TO THE FIRM MASCHINEN-FABRIK MOENUS A. G., OF FRANKFORT-ON-THE-MAIN, GERMANY

SHOE POUNDING-UP MACHINE

Application filed June 12, 1930, Serial No. 460,765, and in Germany March 13, 1929.

The present invention relates to machines for pounding-up lasted shoes for conforming the shoe stock on the bottom and the side of the last adjacent to the edge of the shoe. 5 These machines comprise as a rule a rotary carrier upon which are mounted in circular series a plurality of beating elements which are loosely hung and capable of yielding inwardly against the action of centrifugal force while the machine is in motion. With this 10 rotating pounding-up drum cooperates a side beater which is reciprocated in a path substantially vertical to the axis of the drum. The work is presented hitherto to the beating 15 tools by hand although some abutment or supporting-means for the shoe are generally used. This is very harmful to the attendant inasmuch as the vibrations of the tools are transmitted to his arms. 20 It is the primary object of the present invention to so construct the pounding-up machine as to fully relieve the operator. The principal feature of the invention consists in means provided for supporting and automatically guiding the shoe while it is operated upon by the beating tools. Other features of the invention including certain details of construction and combinations of 25 parts, will be more fully explained in the accompanying description and will then be 30 pointed out in the claims.

Fig. 1 is a side elevation of a machine embodying this invention, some parts being shown in a vertical section. Fig. 2 is a partial cross-section on the line 2—2 of Fig. 1 and Fig. 3 is a like section on the line 3—3 of Fig. 1. Fig. 4 illustrates a mode of operation of the machine. Fig. 5 shows the beating drum and a shoe operated upon. Fig. 6 is a section on the line 6—6 of Fig. 1 some parts being omitted for the sake of clearness. Fig. 7 is a vertical section on the line 7—7 of Fig. 1. Fig. 8 is a partial plane view of the frame 1 and the parts enclosed therein. Fig. 9 is a partial vertical section on line 9—9 of Fig. 8.

The machine-frame consists of three parts 1, 2 and 3. The part 1 accommodates the means for driving the beating tools and for moving the shoe-jack. The part 2 forms the support for the shoe-jack and carries the part

3. In the part 3 there are journaled the pounding-up drum 11 and the side beating tool 66.

The tools are driven by the main shaft 4, the belt or chain 9, the intermediate shaft 6, the pulley 6', the belt 10, the pulley 8, and the shaft 7. To the shaft 7 is fastened the pounding-up drum 11. The side-walls 11' of the drum are connected by bolts 11'' carrying the beating rings 11'''. When the drum is rotating the rings 11'''' are thrown outwardly by centrifugal force and are free to yield when coming into contact with the shoe operated upon. The diameter of the rings grows bigger from the sides to the middle but the thickness and the weight of the rings are so chosen that all individual rings exert the same centrifugal force. The drum 11 as whole has therefore a spherical shape. The shaft 7 is journaled in the walls 3'' of the head 3. The shaft 7 carries also the arms 67, 68, see Fig. 6, which form bearings for the shaft 73, the middle part of which has the shape of a triangular cam 69. This cam rotates within the casing 69' fastened to the arm 67. The casing 69' accommodates the guiding bolt 66' of the side-beating member 66, the working face of which is concave in the vertical direction and convex in the horizontal direction as seen from the Figs. 1 and 4. The arms 67, 68 can swing around the shaft 7 and the pins 67' and 68' engaging the slots 3''' of the walls 3'' limit their swinging movement. The rotation of the shaft 73 is derived from the shaft 7 by means of the sprocket wheels 70, 72 and of the sprocket chain 71. The cam 69 imparts the movement to the beating tool 66. The arms 67, 68 are held in their foremost position by the springs 74 and the weight 80. The springs 74 abut with their front-ends against the said arms and with their rear ends against the member 76 pivoted at 75 in the head 3. The tension of the springs 74 is regulated by the screw spindle 77 which may be rotated by the hand-wheel 78. The weight 80 is fastened to the shaft 83' journaled in the arms 83 rotatable on the shaft 73 and connected by the link 82 with the crank-arm 81' of the hand-lever 81. The lever 81 may be swung on the shaft 7 and

be arrested in the position desired by the engagement of the ratchet 85 of the lever 86 into the teeth 87 of the head 3. By so adjusting the lever 81 the weight 80 may be brought along the line 84 more or less into alignment with the beating-direction of the side pounding member 66 to more or less counteract the blows of the beating member 66.

The shoe-jack consists of a toe support 61 and a heel-support 61' arranged on a plate 62. By means of the hand-wheel 64 having a wedge-part 65 the height of the heel-support may be adjusted. The plate 62 is accommodated in the housing 60 upon a pneumatic tire 63 or upon springs. The housing 60 is adapted to slide in the head-plate 53 of the hollow vertical shaft 52. The vertical position of the shaft 52 can be adjusted by means of the screw threads 56 and the hand-wheel 54 by means of the ball bearing 55 upon the sleeve 50. The sleeve 50 is threaded into the bushing 51 fixed in the part 2. To the lower end of the sleeve 50 is fastened the toothed wheel 31 which is in mesh with the toothed segment 28. To the lower end of the hollow shaft 52 is fastened the toothed wheel 32 in mesh with the toothed segment 29. Within the hollow shaft 52 is accommodated the shaft 57 to the lower end of which is fastened the toothed wheel 33 in mesh with the toothed segment 30. To the upper end of the shaft 57 is fastened the toothed wheel 58 in mesh with a rack 59 provided in a median slot of the jack-housing 60. The toothed segments 28, 29, 30 are rotatable on the fixed shaft 27 and their rear parts 34, 35, 36 are connected by intermediate adjusting members and the links 37, 43, 44 respectively with the levers 24, 25, 26 rotatable upon the shaft 20 fixed in the frame-part 1. The intermediate adjusting members connecting the part 34 with the link 37 consist of the lever 40 pivoted at 40' to the part 34 and of the notched segment 39 swinging about the shaft 38. The lever 40 passes through the slot 41 of the segment and its position relatively to the latter may be adjusted by engaging the snap 42 into any of the notches 39', see Fig. 2. In a similar way the part 36 of the toothed segment 30 is connected to the link 44 by the lever 46 and the notched segment 45, the snap 48 of the lever 46 engaging into the notches 45' of the segment 45, see Fig. 3. The connection of the part 35 with the lever 25 is not shown as it is identical with the connections just described.

A shaft 14 suitably journaled in the frame-part 1 carries the worm gear 13, and the discs 15 and 16. The worm gear 13 is driven by the worm 12 integral with the shaft 4 and is provided on its underside with a cam-groove 17 into which engages the roll 21 of the lever 24 mentioned above. The disc 15 has an upper cam-groove 18 and a lower cam-

groove 19. Into the upper cam-groove 18 engages the roller 22 of the lever 25 and into the lower groove engages the roller 23 of the lever 26. By the means described the lever 24 rotates the toothed gear 31 and the threaded sleeve 50 to lift the head plate 53 with the shoe jack 61, 61'. The lever 25 rotates the gear 32 in order to rotate the head plate 53 and the shoe jack. The lever 26 rotates the gear 33 in order to move the housing 60 horizontally against and from the beating tools. The three levers 24, 25, 26 swing in time relation in order to adapt the path of the shoe to the curvature of the outline of the latter. In the case of changes of the shape and the size of the shoe the adjustments described in connection with Figs. 2 and 3 may be made use of. Moreover the whole head-part 3 may be adjusted in the dove-tail guide 3', see Figs. 1 and 6, by means of the screw-spindle 16' 85 and the hand-wheel 79. Minor changes are met by the resiliency of the pneumatic tire 63 or equivalent springs.

The main shaft 4 may be driven by an electromotor or by a transmission belt as shown 90 in Figs. 7 to 9. The pulley 115 and the coupling-part 5 are keyed to the sleeve 4' rotating freely on the shaft 4. The coupling-part 110 is slidable on the shaft 4 but is prevented from rotating thereon by the key 4''. The spring 111 fastened at 111' to the frame-part 2 and at 111'' to the lever 113 tends to keep the coupling parts in engagement. But these parts can be disengaged by the lever 113 pivoted on the bolt 112. The lever 113 has rollers 113' projecting into a circumferential groove of the hub 114 of the coupling-part 110. The lower end of the lever 113 is pivoted to the bar 116 the free end of which is supported by the knee-lever 125 pivoted to the frame 1 at 105 126. The lever 116 is provided on its underside with a dog 118 adapted to come into contact with a pin 119 of the rotating disc 16. Every time the bar 116 is pushed to the right of Fig. 7 by a pin 119 the coupling becomes 110 disengaged and the machine stops. To bring the machine into operation the free end of the lever 116 is brought out of reach of the pin 119 by depressing the treadle 120 pivoted on the bolt 121 and connected by the link 124 with the said knee-lever 125. If the machine is to be stopped after every full rotation of the shaft 14 the disc 16 is provided with one pin 119 only, but if it is to be stopped after every half of rotation the disc is provided 120 with two pins 119, 119'. The toe and heel supports 61, 61' are so adjusted that the general outline *s* of the ball part of the shoe and the outline *f* of the heel part form with axis *z* of rotation of the head plate 53 angles of the same amplitude *a*. When the treadle 120 is depressed the shoe is moved by the cam-groove 19 from the position A into the position B, the toe of the shoe being first worked upon at 101. The shoe is 130

125

then turned by the cam-groove 18 to the right about the axis α , as seen from Fig. 4, so that the toe is worked upon at 102. The shoe is thereupon simultaneously slightly rotated by means of the groove 18, lowered by the groove 17, and moved underneath the drum 11, so that the part 102' and the part c of the edge k are worked upon, see Figs. 4 and 5.

The shoe is then brought back in the original position shown in full lines in Fig. 4, and the opposite edge of the shoe is worked in a like manner. For pounding up of the heel-part the shoe is shifted into the position A, and after turning about 180° the shoe is moved back into reach of the beating tools. Instead of imparting to the shoe-jack an oscillatory and rotating movement, in the manner just described it is of course possible to only rotate the shoe-jack in a continuous manner once around in order to pound up the toe and heel portions of the shoe.

The machine described may stop after every half of a revolution and can be used for pounding-up the heel-portion of the shoe only. In this case the worm-wheel 13 and the disc 15 must be exchangeable as the cam-grooves must have another configuration if the machine is to stop after a half of a revolution. For stopping the machine after every half of a revolution a pin 119' is diagonally arranged to the pin 119.

What we claim is:

1. In a shoe pounding-up machine, a rotating carrier comprising a plurality of beating members independently yieldingly mounted on the periphery of the carrier, an oscillating beating tool adjacent to and underneath of the carrier, means for supporting the shoe, and means for automatically moving the supporting means and the shoe with its lateral edges past the operating tools.

2. In a shoe pounding-up machine, a rotating carrier comprising a plurality of beating members independently yieldingly mounted on the periphery of the carrier, an oscillating beating tool adjacent to and underneath of the carrier, means for supporting the shoe, and means for automatically rotating the supporting means while the shoe is operated upon.

3. In a shoe pounding-up machine, a rotating carrier comprising a plurality of beating members independently yieldingly mounted on the periphery of the carrier, an oscillating beating tool adjacent to and underneath of the carrier, means for supporting the shoe, and means for automatically moving the supporting means and the shoe in a substantially rectilinear direction while the lateral edges of the shoe are operated upon and in a curvilinear direction while the ends of the shoe are operated upon.

4. In a shoe pounding-up machine, a rotating carrier comprising a plurality of beating members independently yieldingly mounted

on the periphery of the carrier, an oscillating beating tool adjacent to and underneath of the carrier, means for supporting the shoe, means for automatically moving the supporting means and the shoe with its lateral edges past the operating tools, and automatic means for moving the supporting means into and out of the operative position.

5. In a shoe pounding-up machine, a rotating carrier comprising a plurality of beating members independently yieldingly mounted on the periphery of the carrier, an oscillating beating tool adjacent to and underneath of the carrier, means for supporting the shoe, means for automatically moving the supporting means and the shoe with its lateral edges past the operating tools, and means for automatically lifting and lowering the supporting means while the shoe is operated upon.

6. In a shoe pounding-up machine, a rotating carrier comprising a plurality of beating members independently yieldingly mounted on the periphery of the carrier, an oscillating beating tool adjacent to and underneath of the carrier, means for supporting the shoe, and means for automatically moving the supporting means while the shoe is operated upon and comprising a rotating cam, a lever swung by the cam, and a gear on the supporting means rotated by the swinging lever.

7. In a shoe pounding-up machine, a rotating carrier comprising a plurality of beating members independently yieldingly mounted on the periphery of the carrier, an oscillating beating tool adjacent to and underneath of the carrier, means for supporting the shoe, and means for automatically moving the supporting means while the shoe is operated upon and comprising a rack and a gear engaging the rack for relatively moving thereon.

8. In a shoe pounding-up machine, a rotating carrier comprising a plurality of beating members independently yieldingly mounted on the periphery of the carrier, an oscillating beating tool adjacent to and underneath of the carrier, means for supporting the shoe, and means for automatically moving the supporting means while the shoe is operated upon and comprising a rotatable shaft carrying the shoe supporting means, and a screw-threaded sleeve carrying the rotatable shaft adapted to be raised and lowered by rotation.

9. In a shoe pounding-up machine, a rotating carrier comprising a plurality of beating members independently yieldingly mounted on the periphery of the carrier, an oscillating beating tool adjacent to and underneath of the carrier, means for supporting the shoe, means for automatically moving the supporting means relatively to the beating means while the shoe is operated upon, a frame part accommodating the beating device, and means for adjusting the position of the frame part in respect of the shoe-supporting means.

10. In a shoe pounding machine, a rotat-

ing carrier comprising a plurality of beating rings loosely mounted on the periphery of the carrier for movement radially thereof by centrifugal force while the carrier is in motion, the diameter of the rings decreasing from the middle to either side of the carrier.

11. In a shoe pounding machine, a rotating carrier comprising a plurality of independent beating members mounted on the periphery of the carrier, an oscillating beating tool adjacent to the carrier and yielding in a path around the carrier.

12. In a shoe pounding machine, a rotating carrier comprising a plurality of independent beating members mounted on the periphery of the carrier, an oscillating beating tool adjacent to the carrier, a yielding bearing for the tool, and a weight on the bearing adjustable with respect to the beating direction of the tool.

13. In a shoe pounding machine, a rotating carrier comprising a plurality of independent beating members mounted on the periphery of the carrier, an oscillating beating tool adjacent to the carrier, means for supporting and automatically guiding the shoe, and means for automatically stopping the machine after the pounding operation is finished.

14. In a shoe pounding machine, a rotating carrier comprising a plurality of independent beating members mounted on the periphery of the carrier, an oscillating beating tool adjacent to the carrier, means for supporting and automatically guiding the shoe, and means for automatically stopping the machine after the pounding-up of the heel and the toe of the shoe is finished.

In testimony whereof we affix our signatures.

HEINRICH ZWEIFEL.

CARL WILHELM LORENZ MÜLLER.
